UNITED STATES PATENT OFFICE.

CHARLES H. HUGHES, OF SYRACUSE, NEW YORK, ASSIGNOR TO SEMET-SOLVAY COMPANY, OF SYRACUSE, NEW YORK, A CORPORATION OF PENNSYLVANIA.

RETORT COKE-OVEN.

1,055,536.

Specification of Letters Patent. Patented Mar. 11, 1913.

Application filed August 19, 1912. Serial No. 715,736.

To all whom it may concern:

Be it known that I, CHARLES H. HUGHES, a citizen of the United States, residing at Syracuse, in the county of Onondaga and

5 State of New York, have invented certain new and useful Improvements in Retort Coke-Ovens, of which the following is a specification.

My invention relates particularly to the 10 type of oven shown in United States Letters Patent No. 970,720, and the object of my improvements is to provide a simple system of distributing flues for the air of combustion and the waste gases and an arrangement of controlling valves whereby, 15 when the direction of the flow of gas through the heating flues of the oven and through the regenerators is reversed, the air will be admitted through the heated regenerator to the heating flues and burners in 20 the most direct manner without first having to sweep out the waste gases of combustion from a waste gas flue, and no waste gas will continue to be sent through the heated regenerator. 25

My invention will be best understood by reference to the accompanying drawings, illustrating an embodiment thereof, Figure 1 of which shows a vertical longitudinal 30 section through one oven of a block, and Fig. 2 shows a horizontal section on the line 2—2 Fig. 1.

Referring to the drawings, A indicates the oven below which are located two regenerators, 1, 2, the construction being the same for each oven of the block. Below the regenerators are located waste gas flues, 4, 5, and, between these, an air supply flue 3, running longitudinally of the block of 35 ovens. The waste gas flues 4, 5, are connected respectively with the regenerators 1, 2, by passages 7, 10, and the air flue 3, is also connected with the regenerators 1, 2, by passages 8, 9. The passages, 7, 8, are 40 controlled by a single valve 11, so arranged that when one of the passages as, 7, is closed by the valve the passage, 8, is open, and vice versa. The passages, 9 and 10, are controlled in the same manner by valve 12, and 45 the valves 11, 12, are arranged to operate synchronously so that one or the other of the passages, 8, 9, from the air flue 3 is always open so that air is continuously flow-

ing from air flue 3 to one or the other of regenerators 1, 2, and thence to the heating flues of the oven in one direction or the other.

The synchronous operation of all the valves, 11, 12, of the oven block is effected by the following described means. The 60 valves 11, are each connected by a rod, 13, with an arm, 14, secured to a rotatable rod, 15, running along one side of the block, or battery, of ovens and the valves, 12, are in the same manner connected by rods, 16, to 65 arms, 17, secured to a rotatable rod, 18, running along the other side of the block of ovens. At the end of the block of ovens the rods, 15, 18, are provided with means for effecting their synchronous rotation, 70 such as a rod, 19, connected at its ends to levers, 20, 21, secured respectively to rods, 15, 18, and also connected to pistons working in cylinders, 22, 23.

When it is desired to reverse the direction of the gas current through the regenerators and the heating flues of the ovens the rod, 19, is moved in one direction or the other as the case may be, thus rotating the rods, 15, 18, and moving all the valves, 75 11, 12, in the same direction.

One set of passages from the air flue, 3, as, 8, is opened and the other set of passages, 9, is closed. At the same time the passages, 10, are opened and the passages, 85 7, are closed. Thus the waste gas begins to flow through regenerator, 2, and into flue 5, while air, which is always under pressure in flue, 3, begins to flow directly therefrom into the heated regenerator, 1. By 90 means of a chain, 24, connected with the rod, 19, and passing around the spindle of valve, 25, which controls the outlets of waste gas flues, 4, 5, one of these flues is closed and the other opened by the same movement 95 which opens and closes the passages, 7, 10.

It will be understood from the foregoing that upon shifting the position of the valves, 11, 12, reversal of the gas current is instantly effected, without any tendency of 100 the waste gas to continue to flow through the heated regenerator, and the supply of air for combustion enters the heated regenerator instantly and directly with no admixture with waste products of combustion except for the negligible quantity con-

tained in the regenerator, so that the burners are constantly supplied with air and there is no loss of combustible gas.

When it is desired to cut an individual oven out of operation, as for repairs, the rods, 13, 16 may be disconnected from the arms 14, 17, and the valves moved so as to close the passages 7, 10. Cold air will then circulate through the heating flues and the oven is thus made easily accessible.

What I claim as new and desire to secure by Letters Patent is:—

1. The combination with a horizontal flue, retort coke oven of a pair of regenerators located below the oven and parallel thereto, two waste gas flues and an intermediate air flue located below the regenerators, a passage connecting each of the waste gas flues with one of the regenerators, passages directly connecting the air flue with both regenerators, valves controlling said pas-

sages and means for moving said valves so as to synchronously shift the connections between the regenerators and said flues.

2. The combination with a retort coke oven having horizontal heating flues connected in series of a pair of regenerators connected in series with the heating flues, two waste gas flues, means for alternately connecting the regenerators with the waste gas flues and an air flue located intermediate the waste gas flues and provided with passages leading directly to each of the regenerators.

In testimony whereof, I have hereunto subscribed my name, this 7th day of August A. D., 1912.

CHARLES H. HUGHES.
